US00D584331S

(12) **United States Design Patent**
Chen

(10) **Patent No.:** **US D584,331 S**
(45) **Date of Patent:** **** Jan. 6, 2009**

(54) **EYEGLASSES**

(75) Inventor: **Ward Chen**, Pomona, CA (US)

(73) Assignee: **Jay-Y Enterprise Co., Inc.**, Pomona, CA (US)

(**) Term: **14 Years**

(21) Appl. No.: **29/248,348**

(22) Filed: **Aug. 11, 2006**

(51) **LOC (9) Cl. 16-06**

(52) **U.S. Cl. D16/315**

(58) **Field of Classification Search** D16/101, D16/300-342; D29/109-110; D24/110.2; 351/41, 44, 51-52, 62, 158, 92, 103-123, 351/140, 153; 2/426-432, 447-449, 441, 2/434-437

See application file for complete search history.

(57) **CLAIM**

I claim the ornamental design of the eyeglasses, as shown.

DESCRIPTION

FIG. 1 is a perspective view of the eyeglasses.

FIG. 2 is a front view of the eyeglasses.

FIG. 3 is a top view of the eyeglasses.

FIG. 4 is a side view of the eyeglasses; and,

FIG. 5 is a side view of the eyeglasses.

The broken lines shown in FIG. 3 are for illustrative purposes only and form no part of the claimed design.

1 Claim, 3 Drawing Sheets
